UNITED STATES PATENT OFFICE.

HARRY SCHLESINGER, OF DES MOINES, IOWA, ASSIGNOR TO SCHLESCO-SHURE MANUFACTURING COMPANY, OF DES MOINES, IOWA.

SAFETY DEVICE.

Application filed April 26, 1926. Serial No. 104,683.

The object of my invention is to provide a safety device for dry cleaning plants or other places where tanks are provided that are subject to explosion and fire.

5 More particularly my invention relates to a device wherein in case of an explosion a valve is opened for permitting steam to pass into the tank into which the explosion occurs and prevents damage by fire and to 10 permit the valve to be operated in case of a fire without an explosion.

It may be here mentioned that in gasoline supply tanks or dry cleaning plants where gasoline is used in washing machines, 15 that when an explosion takes place an explosion door ordinarily mounted upon the tank is thrown open and it is my object to operate my safety device upon the opening of the explosion door for opening the valve 20 and permitting my device to function.

With these and other objects in view, my invention consists in the construction, arrangement and combination of the various parts of my invention, whereby the objects 25 contemplated are attained, as hereinafter more fully set forth, pointed out in my claims, and illustrated in the accompanying drawings, in which:

Figure 1, is a top plan view of a tank or 30 the like with my improved device installed thereon adjacent to the explosion door.

Figure 2, is a sectional view taken on line 2-2 of Figure 1, parts being shown in dotted position when the device is opened.

35 Figure 3, is a detail sectional view taken on line 3-3 of Figure 2 and

Figure 4, is a sectional view taken on line 4-4 of Figure 2.

In the accompanying drawings I have 40 used the reference numeral 10 to indicate generally a tank of any suitable kind which may be a gasoline supply tank such as is used for oil storage purposes or a washing machine of the type used in dry cleaning 45 plants.

The tank 10 is usually provided with an explosion door 11 which is thrown open when an explosion occurs within the tank.

My device is mounted adjacent to the explosion door and is secured to the tank in the manner I will now describe.

The tank 10 is provided with the opening 12 which is slightly less in size than the cover 13 upon which is mounted the mechanism of my safety device.

The covering 13 is secured in position by means of bolts or the like 14.

Mounted within the covering 13 is a bell shaped member 15 opening into the tank 10.

The outside of the bell shaped member 15 is screw threaded as at 16 and receives a nut or the like 17 with the covering 13 arranged therebetween as clearly shown in Figure 2 of the drawings.

The bell shaped member 15 is formed with 65 a valve seat 18 having a valve member 19 mounted therein and resting upon an adjustable member or bolt 20.

A lever 21 is mounted within the tank and pivotally connected to a pair of spaced lugs 70 or ears formed upon the member 15.

The covering 13 includes a cap or the like 22 which has an opening 23 therein through which an adjustable hook arm 24 is extended.

The end of the lever 21 is formed with a 75 notch 25 which receives one end of a fusible link 26. The free end of the fusible link 26 is connected to the hook arm 24.

When the adjustable bolt 20 is mounted upon the lever 21 and retains the valve 19 80 in closed position, the parts are in the position shown in solid lines in Figure 2 of the drawings.

The nut member 17 is formed with a number of openings 27 wherein a tool may be 85 inserted for rotating the nut and one of these openings is screw threaded.

Mounted within the screw threaded opening is a stud 28 having an arm 29 formed thereon.

The arm 29 is bifurcated as at 30. Pivotal- 90 ly mounted between the bifurcated portions 30 of the arm 29 is a pivoted arm 31.

The pivoted arm 31 is forked at its outer end as at 32 and the hook arm 24 extends 95 through the fork portion 32 as clearly shown in Figures 2 and 4 of the drawings.

The hook arm 24 is formed with a screw threaded portion upon which is mounted a pair of nuts 33 wherein the hook arm 24 may 100 be locked or adjusted relative to the pivoted arm 31.

The pivoted arm 31 is formed with a portion 34 which extends rearwardly or beyond the arm 29.

The stud 28 is formed with a shank 35, upon which is mounted a cam member 36. The cam member 36 is designed to extend upon the portion 34 of the pivoted arm 31 and when in the position shown in Figure 3 110

of the drawings, will prevent the pivoted arm 31 from pivotal movement.

The cam 36 is formed with an opening in which is mounted a rod or bar 37 and held in position by a set screw 38. The bar 37 is positioned so that it extends above the explosion door 11 and in case of an explosion and the door is raised or thrown open, then the bar or rod 37 is moved or swung to the position shown in dotted lines in Figure 1 of the drawings, causing the cam member 36 to swing clear of the portion 34 and permitting the pivoted arm 31 to move to the position shown in dotted lines in Figure 2 of the drawings.

The bar or rod 37 may be inserted either on the right hand side or left hand side of the cam 36 and thus my device may be mounted upon either side of the explosion door 11.

When the explosion door 11 is thrown open by the force of the explosion, it automatically causes the cam 36 to disengage the portion 34, permitting the arm 31 to drop as well as the lever 21, opening thereby the valve 19.

The bell shaped member 15 is in communication with a pipe 39 through which steam may be admitted into the tank 10 when the valve 19 is moved to open position.

It may be here mentioned that in case of a fire the fusible link 26 will melt and this will permit the lever 21 to move, unseating the valve 19 from the seat 18.

My device will operate either when an explosion takes place instantly or in case of a fire.

It may be here mentioned that the operation of my device by cause of an explosion is quicker than by fire.

In case of a fire or an explosion, live steam is permitted to pass into the tank through the pipe 39 and bell shaped member 15.

It will be noted that the valve 19 is adjustably mounted and that the hook arm 24 is also adjustably mounted, thus giving me a device that can be easily installed and properly adjusted to function under predetermined conditions.

It will be further noted that the entire device is mounted as a unit upon the tank 10.

Some changes may be made in the construction and arrangement of the various parts of my invention, without departing from the real spirit and purpose of my invention, and it is my intention to cover by my claims, modified forms of structure or use of mechanical equivalents, which may be reasonably included within their scope.

I claim as my invention:

1. A safety device for tanks or the like having an explosion door comprising a valve seat and a movable valve member for controlling the injection of a fire extinguishing element into said tank, means for retaining the valve member in closed position, said means

comprising a pivoted lever having a portion to engage the movable valve member, a second pivoted lever connected to the first lever by a fusible link, located within said tank, a swinging cam adapted when in normal position to engage said second lever for maintaining it in position to prevent movement of the movable valve member, said cam having an arm adapted to be struck by the explosion door for moving the cam from such normal position for rendering said first means inoperative.

2. In a device of the class described adapted to be operated by an explosion door of a tank, a valve normally closed and adapted when open to admit a fire extinguishing element to said tank, means for holding the valve closed including a lever, a pivoted arm, a fusible link positioned within said tank and connecting the free ends of the lever and the arm and an adjustable screw on the lever adapted to hold the valve in closed position, cam means engaging the pivoted arm for preventing movement thereof and means in connection with said cam means and operable by the explosion door when thrown open for causing the cam to disengage the pivoted arm to move for opening the valve.

3. In a device of the class described adapted to be operated by an explosion door of a tank, a valve normally closed and adapted when open to admit a fire extinguishing element to said tank, means for holding the valve closed including a lever, a pivoted arm, a fusible link located within said tank and connecting the free ends of the lever and the arm, cam means engaging the pivoted arm for preventing its movement and means in connection with said cam means and operable by the explosion door for causing the cam to disengage the pivoted arm for opening the valve.

4. A safety device for tanks or the like having an explosion door comprising a valve member, means for retaining the valve member in closed position and means operable by the explosion door for rendering said first means inoperative, said first means including a fusible link member located within said tank, said last means including a cam member adapted to extend over a portion of the means for retaining the valve closed, a rod mounted in the cam member and extending away therefrom and over the explosion door so that movement of the door will strike against the rod and throw the cam member free of said portion and permit the valve to open for admitting a fire extinguishing element to the interior of said tank.

5. In combination with a container having an openable explosion door thereon, a safety device of the character described comprising a valve mounted adjacent said explosion door, means of connecting a source of fire extinguishing substance to said valve whereby

opening of the valve will admit said substance to the interior of said container and means overhanging said door and adapted to be struck by said door when thrown open for 5 opening said valve, said means comprising mechanism for holding the valve shut and a lock for said mechanism, said mechanism including a fusible link located within said container, said lock being actuated by the means 10 overhanging the explosion door for rendering the lock inoperative when said last means is struck.

6. In combination with a container having 15 an explosion door thereon, a safety device comprising a valve body, a seat therein, a valve member normally engaging said seat, a lever for engaging said valve member, an arm pivoted on said body member, cam means 20 engaging said arm to normally maintain said arm in a predetermined position, a fusible link located within said container and connecting said lever for said arm together and serving in conjunction with said link to maintain 25 said valve member against said seat, and means extending from said cam and adapted

to be struck by said explosion door when thrown open by an explosion for moving said cam to disengage said arm whereby said valve will be opened.

7. In combination with a container having 30 an explosion door thereon, a safety device comprising a valve body, a seat therein, a valve member normally engaging said seat, for preventing a fire extinguishing element from discharging through said valve, a lever 35 for engaging said valve member, a holding arm pivoted on said body member, cam means engaging said arm to normally maintain said holding arm in a predetermined position, a fusible link located within said container and 40 connecting said lever and said holding arm together for serving in conjunction with said link to maintain said valve member against said seat and an actuating arm extending from said cam and adapted to be 45 struck by said explosion door when thrown open by an explosion for moving said cam to disengage said holding arm whereby said valve will be opened.

HARRY SCHLESINGER.
